UNITED STATES PATENT OFFICE.

THOMAS E. PRAY, OF CHICAGO, ILLINOIS, ASSIGNOR TO GOODMAN MANUFACTURING COMPANY, OF CHICAGO, ILLINOIS, A CORPORATION OF ILLINOIS.

ELEVATING MECHANISM.

Original application filed April 6, 1922, Serial No. 550,192. Divided and this application filed December 30, 1924. Serial No. 758,939.

This invention relates to improvements in elevating mechanisms, especially adapted for use with mining machines, although it is not limited to such use.

5
8 The present invention is a division of my application for improvements in mining machines, filed April 6, 1922, bearing Serial Number 550,192.

10 The principal object of the present invention is to provide an improved toggle mechanism for raising and lowering the cutting mechanism and an improved arrangement of tension means coacting with the toggle mechanism to assist in raising the 15 cutting mechanism from its lowermost position.

19 My invention may be best understood by reference to the accompanying drawings, in which:

20 Figure 1 is a side elevation of a machine embodying my invention, with the outer end of the cutter arm omitted;

25 Figure 2 is a plan view of the machine with the cutting element and supporting plates removed to show the operating mechanism of the elevating device;

30 Figure 3 is a side view drawn to a larger scale than Figure 1 and showing the truck and elevating mechanism in cross section.

35 This view also indicates in dotted lines the position of the cutting element when raised; and

Figure 4 is a detail of the tension means forming a portion of the elevating device.

40 In the form in which my invention is embodied as illustrated in the drawings, a cutting element 10 is mounted on a truck frame 11, having wheels 12, 12, adapted for engagement with tracks 13, 13. The cutting

45 element may be of any suitable construction including a kerf cutting device, draft device, and a motor for operating these devices. In the form illustrated, I prefer to use for the cutting element a shortwall mining machine of a well-known type adapted

50 normally for movement on the mine floor and having a forwardly projecting cutter arm 14 provided with a cutter chain 15 and with a suitable winding drum 16 having

55 a draft cable 17 wound thereon to move the machine angularly as will hereinafter more fully appear. A motor having suitable operative connection with the cutter chain 15 and the winding drum 16 is mounted in

a casing 18 at the rear end of the cutting element 10. Details of this motor and operative connections need not be described as they form no part of the present invention. When used on the mine floor, as suggested, the machine slides upon its bottom 60 face 19 in the usual manner.

55 In the form shown, the cutting element is carried on the truck at all times. While the machine is being transported from place to place, the cutting element is arranged longitudinally of the truck body as shown in Figures 1 and 3, but when cutting a kerf

65 the cutting element is swung angularly about a fixed pivot on the truck frame. Details of construction whereby this pivotal movement

70 may be accomplished are shown in Figure 3, in which it will be seen that a pivotal stud 20 is carried at the rear end of the cutting element and preferably integral with the end plate 21 of the motor casing 18. The cutting element rests on a plate 22 which plate

75 in turn rests on a bed plate 23 forming the top portion of the elevating device which will hereinafter be described. It will be noted that the stud 20 extends through the

80 plate 22 and provides bearing to permit angular movement thereof in a substantially horizontal plane. Said stud also has bearing in an annular plate 24 forming a part of the bed plate 23. The arrangement

85 is such that the cutting element may be pivotally moved on stud 20 with respect to the plate 22 and with the bed plate 23. The plate 22 may also be pivoted on the common

90 axis of the stud 20 with respect to the cutting element and the bed plate 23. The forward edge 25 of the plate 22 is preferably curved and is retained in a guide member 26 attached to the forward end of the cutting element. The forward edge 27 of

95 the bed plate 23 is similarly curved and retained in a guide member 28 attached to the plate 22. Suitable means for limiting the lateral swinging movement of the cutting element and plate 22 with respect to the bed plate 23 are provided, as for instance a pair of chains 29 and 30. The ends

100 of chain 29 are connected on hooks 31, 32, at the forward end of the cutting element 10 and the plate 22, respectively. The ends of chain 30 connect hook 32 on plate 22,

105 with another hook 33 on the bed plate 23. The length of the chains may be readily

adjusted by engaging any one of the links with the hooks as desired, so as to permit any desired angular movement of the cutting element with respect to the truck to 5 cut a predetermined width of room or entry.

The elevating mechanism includes a toggle device having as its principal elements a plurality of toggle members 35, 35, pivotally connecting the bed plate 23 and the 10 truck frame 11 at points 36, 36, adjacent the front and rear of the machine respectively, and a longitudinally movable toggle member 37 adapted to coact with the toggle members 35, 35, to raise the bed plate and cutting 15 element as indicated in dotted lines in Figure 3. This general arrangement of toggle members is similar to that disclosed in my copending application for U. S. Letters Patent, bearing Serial No. 489,763, filed 20 August 4, 1921.

In the present construction I provide an improved arrangement of tension means coacting with the toggle mechanism and arranged to be placed under tension by the 25 weight of the cutting mechanism as it approaches its lowermost position and to assist in the raising of the mechanism from its lowermost position when the toggle members are at the maximum angle with respect to 30 each other and require the greatest amount of power to be operated. This tension device is shown in detail in Figures 2 and 4 and comprises a yoke 40 engaging a movable head 41 of a longitudinally movable rack 35 42 which is pivotally connected at 43 to the toggle member 37. Means for actuating this rack will be hereafter described. A pair of rods 44 are connected to the ends of the yoke 40 and extend into cylinders 45, 45, 40 mounted on the truck member 11. A detail of one of these cylinders is shown in Figure 4, in which it will be seen that the rod 44 is provided at its inner extremity with a collar 46 secured by suitable means such as 45 a bolt 47. A smaller collar 48 is fixed on the rod by suitable means such as a pin 49 at a point intermediate the collar 46 and the bearing shoulder 50 at the end of the cylinder through which the rod 44 extends. 50 A collar 51 larger than collar 48 is loosely mounted on the rod 44. A compression spring 52 is interposed between the collar 51 and the shoulder 50 of the cylinder. A compression spring 53 is interposed between 55 collar 46 and collar 51.

In Figure 4 the rod 44 is shown in the same position as in Figures 1 and 3, with the elevating mechanism in its lowest position, in which position springs 52 and 53 60 are under maximum compression and the movable collar 51 is in engagement with the fixed collar 48. The spring 52 exerts its pressure directly on rod 44 through collars 51 and 48, said spring being of sufficient 65 strength and stiffness to maintain spring

53 under full compression. In the initial movement of the elevating mechanism, therefore, the full tension of spring 52 is exerted to assist in the upward movement thereof, until the point is reached where the tension 70 of said spring is partially spent, and becomes equal to the tension of spring 53, at which point, both springs become operative and begin to expand simultaneously, causing collar 51 to move slowly away from fixed 75 collar 49.

During the downward movement of the cutting mechanism, the action of the springs is manifestly the reverse of that above described, that is to say, both springs are compressed simultaneously at first, but spring 80 53, being the lighter, is compressed more rapidly than spring 52, and collar 51 is brought into engagement with collar 49 before the end of the stroke is reached, so that 85 the final downward thrust of the toggle mechanism is taken up entirely by the heavier spring 52. By means of the arrangement of springs just described, a maximum tension is provided where it is most needed, 90 at the beginning of the stroke. Springs of varying tensions may be provided to suit requirements as to the weight of the cutting mechanism and power available to lift the same. Two, three or more sets of springs 95 of various sizes and tensions may be provided and the stroke of the springs may be of any length desired. For most purposes, however, it is only necessary to assist the action of the toggle mechanism through a 100 small portion of its upward movement. In the form herein illustrated, it will be seen in Figures 2 and 3 that endwise movement of yoke 40 is limited by the cylinders 45, 45, whereas the head 41 of rack member 42 105 continues its forward movement considerably beyond this point, as shown in dotted lines in Figure 3. The yoke 40 remains in position to be engaged by the head 41 when the mechanism is again lowered. 110

The mechanism for controlling and actuating the elevating device is shown in Figure 2 and includes a pair of pinions 60, 60, engaging the rack member 42, and operatively connected to a crank 61 at the rear end of the truck body 11. This crank is adapted to fit on a squared pin 62. This pin also forms, when coupled at its forward end 62^a with the motor shaft 64, a driving connection between the motor and the truck for propelling the latter. In the arrangement illustrated, the machine is propelled only when the cutting element is in its lowermost position, and the elevating mechanism is inoperative. Furthermore, it is desirable to operate the elevating mechanism only when the driving connection between the cutting mechanism and truck is disengaged. Consequently, the handle 61 may be operated through the same gearing which is used 120 125 130 135

to propel the truck, so that the elevating mechanism may be actuated without interfering with the driving mechanism. Details of the elevating and driving mechanism are 5 as follows:

The squared pin 62 fits through and drives worm 63 which is mounted to turn on a longitudinal axis. Worm 63 is meshed with worm gear 64 on shaft 65 mounted on a 10 transverse axis. A second shaft 66 is mounted parallel with shaft 65 and is driven therefrom through gears 67 and 68. A second gear 69 is carried on the end of shaft 66 opposite gear 68. A transverse driving 15 shaft 70 is mounted adjacent shaft 66, and is provided with chain sprockets 71, 71, keyed on opposite ends thereof and having driving connection with the truck wheels 12, 12, through chains 72, 72. A chain sprocket 20 73 is loosely mounted on the shaft 70, and has driving connection with the pinions 60, 60, of the elevating mechanism through a chain 75, chain sprocket 76 and shaft 77.

Further details of the driving mechanism 25 need not be described as they form no part of the present invention, although it may be pointed out that when the truck is not being propelled, and the driving mechanism is consequently inoperative, the handle 61 30 may be utilized to raise or lower the elevating mechanism through chain 75 and pinions 60, 60, which operate the rack 42 of the toggle mechanism already described. The worm 63 and gear 64 are of the self-

locking type, so that the elevating mechanism may be maintained in any desired position while operating the same. A ratchet device 79 of any suitable construction is also associated with the shaft 77 to maintain the elevating mechanism in any desired position, particularly when the operating gearing above described is disconnected.

Although I have shown and described one form in which my invention may be embodied, it will be understood that the arrangement and construction of the various parts may be altered without departing from the spirit and scope thereof. Furthermore, I do not wish to be construed as limiting myself to the specific construction illustrated 50 excepting as it may be particularly limited in the appended claim.

I claim as my invention:

In combination with a toggle device and means for actuating the same, a tension device comprising a movable member adapted to be operatively connected with said actuating means, two springs of different strengths arranged end to end and interposed between said movable member and a fixed abutment, 55 the lighter spring engaging said movable member, and means limiting the compression of said lighter spring respective to said movable member.

Signed at Chicago, in the county of Cook 60 and State of Illinois, this 27th day of December, A. D. 1924.

THOMAS E. PRAY.
